TIE HANGER

Gary Hellinger, Riverdale, and Issac Zelcer, Brooklyn,
N.Y., assignors to Leeds Ltd., Hackensack, N.J.

Filed Oct. 24, 1965, Ser. No. 87,904

Term of patent 14 years

(Cl. D80—8)

FIGURE 1 is a perspective view of the tie hanger embodying our new design,

FIG. 2 is an enlarged elevational view thereof, and
FIG. 3 is a side edge view thereof.

The broken line representation of ties in FIG. 1 is for purposes of illustration only.

We claim:

The ornamental design for a tie hanger, substantially as shown and described.
